EYECUP

Saturnino Tofé Bonilla, New York, N. Y.

Application August 4, 1941, Serial No. 405,394

2 Claims. (Cl. 128—249)

This invention relates to eye cups and more particularly to a cup in which means is provided for effectively removing foreign matter from the eye of a person, and it consists in the constructions, arrangements and combinations herein described and claimed.

It is the cardinal object of the invention to provide an eye cup having a three-fold use, namely, one which may be used to merely rinse the eye; to project a spray of water to the eye; or to create a suction action so as to withdraw water or cleansing fluids which were previously injected into the eye, thereby removing any foreign matter.

It is a still further object of the invention to provide an eye cup of extreme simplicity in manufacture, the parts being detachably related for cleansing purposes.

Additional objects, advantages and features of invention will be apparent from the following description, considered in conjunction with the accompanying drawing, wherein

Figure 1 is a side elevation of the eye cup,

Figure 2 is a longitudinal sectional view thereof,

Figure 3 is a vertical section of a stopper-valve device employed in the cup,

Figure 4 is a similar view of a further valve of the device,

Figure 5 is a top plan view of the device,

Figure 6 is a vertical section of a modified form of the device.

There is illustrated an eye cup generally indicated by the reference character 10, consisting of a cup body 11 of usual exterior contour and construction as found in eye cups now on the market adapted to snugly seat in the socket of an eye. The base of the cup, however, is formed with a projected shank 12 having a substantial, central opening 13 and upon the exterior of the shank, there is a rabbet as at 14 for a purpose now to be explained.

A collapsible bulb 15 is provided, open at the ends, one of which is engaged and frictionally seated within the rabbet 14 of the shank, and in the other end a valve cage 16 is engaged.

The valve cage 16 is provided with an axial port 17, forming communication for passage of air to the interior of the bulb. Upon the inner end of the cage 16 a flap valve 18 is secured, the latter being provided with small projections 19 maintaining the valve in spaced relation with respect to the port 17.

A stopper-valve 20 is adapted to be positioned within the opening 13, and in the present in-

stance is shown as having an axial port 21 within which the stem 22 is reciprocably mounted. The stem 22 is provided with flat heads 24 adapted to retain the stem in the port 21. The stopper valve 20 is provided with a flap valve 23 adapted to be unseated upon compression of the bulb 15, as will be explained.

The operation of the device will be readily understood from the following description. When the eye cup is used for rinsing the eye, the cup is partly filled with water and adjusted to the socket of the eye as is customary. However, where it is desired to project a spray of cleansing fluid around the eyeball, pressure is exerted on the bulb so as to collapse it, which will cause upward movement of the flap valve 23, air being drawn inwardly through the port 17 at the base of the bulb. Air will pass upwardly through the port 21 of the stopper valve 20 and through the liquid in the cup 11 in the form of bubbles which pass into and around the eye, effecting a cleansing action. When pressure is released upon the bulb, the valve 20 will close the port 21 so that a suction action will not be created upon the eye.

Where foreign matter may have gained access to the eye a vacuous action is desirable to dislodge and withdraw such matter. In such a situation the stopper-valve 20 is removed from the cup, and the bulb and cup filled with liquid to approximately one-fourth of the capacity of the cup. A finger is now placed over the port 17 and the bulb compressed to deliver the liquid to the eye. Expansion of the bulb, upon release of pressure, will create a suction upon the liquid, drawing it back into the bulb, and since the liquid was forced gently in and around the eyeball, the foreign matter will be withdrawn with the liquid. The operation may be repeated as desired.

The stem 22 of the valve is of such length as to be readily grasped for removing the stopper 20, as is required for cleansing and otherwise.

The eye cup and bulb has been described as formed as separable elements, but obviously the parts can be formed as an integral structure, as shown in Figure 6. In this instance, the cup and compressible bulb are shown as formed of rubber as a unitary device and, since the structure is otherwise the same as previously described, corresponding parts have been designated by primed reference characters.

While I have specifically shown and described my construction of eye cup, this is by way of illustration only, and I consider as my own all

such modifications in structure as fairly fall within the scope of the appended claims.

I claim:

1. An eye-cup comprising a cup body having a port opening upon the cup body, a stopper seated within said port for closing the port, said stopper having a valve therein operable to admit air to said cup, said stopper being removable through the upper open end of the cup body, and an open-ended collapsible bulb having one end secured to the port of the cup body, and the other end having a removable air intake valve.

2. An eye-cup comprising a cup body having

a rabbeted shank, said shank having a port opening upon the cup body, a stopper removably seated within said port for closing the port, a headed shank reciprocably mounted in the port of the stopper and movable to admit air into the cup body, said shank being of a length to be moved a substantial distance outwardly of the stopper, whereby the shank may be grasped for removal of the stopper from the cup body, and an open ended collapsible bulb having one end secured within the rabbet and the other end having a removable air inlet valve.

SATURNINO TOFÉ BONILLA.
